LELAND H. HILL, OF SHARON, PENNSYLVANIA, ASSIGNOR TO WESTINGHOUSE ELECTRIC & MANUFACTURING COMPANY, A CORPORATION OF PENNSYLVANIA

TRANSFORMER COOLING SYSTEM

Application filed February 14, 1928. Serial No. 254,218.

My invention relates to transformer cooling systems and comprehends an arrangement for applying a cooling medium to the heat-radiating units traversed by the insulating liquid enveloping the transformer.

In accordance with my invention, there is provided an individual blower unit for each radiator or group of radiator tubes.

It is characteristic of my invention that it has marked advantages over other schemes by virtue of its low cost, compact size, efficient operation and flexibility.

It is also characteristic of my invention that existing apparatus may be improved by mounting individual blowers constructed in accordance with my invention thereon, without affecting the apparatus.

Individual air blowers, constructed in accordance with my invention, may be mounted in any suitable position with respect to the radiator unit and may be adapted to force air in any direction along the walls of the radiator tubes, but I prefer to mount the individual blowers on about the center of the transformer radiator bank and to arrange the deflecting blades to cause the air to move upwardly along the walls of the tubes because I have found this to be the most effective disposition of the blower.

It will be understood that my invention is applicable in any application where it is desirable to provide oil-immersed, self-cooled transformers, with means for blowing air on the cooling surface to increase its emissivity.

In general, my invention is applicable to four types of equipment: (1) for use in localities in which high ambient temperatures are liable to be occasionally encountered; (2) to take care of occasional peaks in loading, for example, a 30% overload for several days out of the whole year; (3) as a means for providing spare capacity to be used in case of emergency; and (4) for use with very large transformers where lack of space on the tank precludes the necessary number of radiators for self-cooling without making the case unusually large.

My invention may be more readily understood if the accompanying drawings are

referred to in connection with the following description.

In the drawings, Figure 1 shows a transformer having individual air blowers mounted on the radiators in accordance with my invention.

Fig. 2 is a view, in cross section, of an individual blower constructed in accordance with my invention and mounted on a radiator.

Fig. 3 is a view in side elevation of the blower shown in Fig. 2 and having a side portion thereof removed, and

Fig. 4 is a view in cross section taken on the line IV-IV of Fig. 3.

Referring to Fig. 1, auxiliary air blast equipment constructed in accordance with my invention comprises individual blowers 1 that are mounted on each radiator 2 through which passes an insulating liquid medium 33, such as oil, said medium passing toward and from a casing 4 through lower and upper pipes 3. Disposed within the casing 4 is suitable transformer equipment or the like, not shown, which is energized through conductors electrically insulated from the casing 4 by insulators 5, the casing, ordinarily, being constructed of a metallic material, such as steel.

The aforesaid liquid medium envelops the transformer equipment, the latter, during operation, elevating the temperature of said medium 33 which, thereupon, circulates through the radiators 2. The radiators 2 comprise a plurality of spaced tubular members collectively providing a large radiating surface whereby the liquid medium 33 traversing them may be cooled.

As pointed out above, it is sometimes desirable and advantageous to increase the cooling effect of the radiators 2 by a co-acting air blast or a plurality of air jets. To this end, I mount the individual blowers 1 on the radiators 2. Each of the blowers 1 is provided with a fan 6 and an electric motor 7 for driving the fan. The motor 7 may be started and stopped either manually or automatically. A preferable arrangement for driving the motor 7 comprises a temperature-responsive thermal re-

lay mounted within a casing 8 on the side of the tank 4. The temperature-responsive relay operates to automatically close an electric circuit to start the motor 7 when the temperature of the aforesaid liquid medium within the transformer casing reaches a predetermined magnitude. The electrical conductors for controlling the operation of the fan may be enclosed in a suitable housing such as a pipe 9 that is supported by straps 10 secured to the transformer casing 4. The fan 6 is preferably similar to the well-known exhaust fan and is mounted in the outside end of a sheet metal conduit or casing structure 11. The motor 7 driving the fan 6 is preferably a relatively small motor that is totally enclosed and is impregnated to make it moisture-proof.

Deflectors 12 may be provided in the outer end of the casing 11 which permit the entrance of air but deflect rain.

The motor 7, preferably, is supported in a frame 13 that, in turn, is secured to the casing 11, each of the latter, in turn, being secured to a radiator 2 by bolts 14, or the like, extending between the radiator tubes 15 and being secured to flanges 16 of the casing 11. Baffle walls 17 are provided on the respective sides of each radiator 2 within the casing 11 and are retained in position by the lower bolts 14 between the lower flanges 16 of the casing 11 and the outer surfaces of the tubes 15, Figs. 3 and 4. The baffle walls 17 bridge the spaces between the upper and lower flanges 16 except for a gap 18 which forms an air outlet port that extends between the upper edge of the baffle wall and the lower edge of the upper flange, Fig. 4.

Another barrier 19 that extends from the top to the bottom of the casing 11 is provided for deflecting and guiding the air from the fan 6 to the sides of the casing 11 as indicated by the arrows in Figs. 2 and 3.

In operation, the fan 6 draws cool air from the atmosphere through the openings between the deflectors 12 and forces it through the openings 18 into the space between the radiator tubes. The air currents from opposite sides of a radiator are directed by the casing 11 to form streams that meet at an angle and form a resultant current of air that moves upwardly along the sides of the tubes of the radiator 2. This action tends to decrease the temperature of the surfaces of the radiator tubes which, in turn, results in a cooling of the liquid medium flowing through the tubes in the usual manner.

Individual radiator blower equipment constructed in accordance with my invention has many advantages over the type using a duct system supplied from a single blower. In the first place, the reliability factor is very high. The possibility of

all of the units being out of commission at once is very remote. With my system, if one motor or fan becomes inoperable, a large percentage of the air blast equipment, namely, the individual units, on each of the other radiators is still available. For example, in large units where 10 to 20, or more, radiators are utilized, the loss of one unit reduces the effectiveness of the air blast only 10% or 5%, as the case may be. Where a single blower is utilized for the whole transformer and the motor becomes inoperable, the air blast equipment is incapacitated 100%. Individual radiator blowers constructed in accordance with my invention have the additional advantage that separate blowers may be kept on hand at very slight cost and may be mounted in place whenever needed.

The maintenance of my individual radiator blowers is also comparatively small, due to the decreased jointing necessary for the steel work. The individual blowers may be easily removed and the transformer jointed as an ordinary unit. Due to the small length of the conducting ducts of the individual radiator blowers, the operating losses are relatively small in comparison with the operating losses of blower systems wherein long conducting ducts are necessary.

As indicated above, individual radiator blowers constructed in accordance with my invention are advantageous by virtue of the fact that they may be readily mounted on existing transformers. By this means, an inexpensive and efficient transformer may be obtained from an old unit. The possible increased efficiency materially depends upon the design of the particular transformer but will generally be between 25 and 35%.

It will be appreciated by those skilled in the art that the air blowers may be mounted on the radiators in the mid-portion thereof as shown or near the bottom or top-portion thereof as may be found most convenient and desirable.

The blowers also may be arranged to blow air downwardly along the tubes as well as upwardly or to blow air both downwardly and upwardly at the same time.

The auxiliary air blast equipment is easily arranged for automatic control, whereby the blowers are started as soon as a predetermined oil temperature is reached and stopped when the equipment is no longer required.

Various changes and modifications may be made in my invention without departing from the spirit and scope thereof, as set forth in the appended claims.

I claim as my invention:

1. The combination with a casing for containing a liquid medium, of a radiator con-

5 nected to said casing and traversed by said liquid medium, a casing embracing a portion of said radiator and provided with air outlet ports on opposite sides thereof, a fan mounted within said casing for producing a current of air, and means for directing said air through said outlet ports and toward the radiator.

10 2. The combination with a casing for containing a liquid medium, of a radiator connected to said casing and traversed by said liquid medium, a casing embracing a portion of said radiator, a fan mounted within said casing for producing a current of air, 15 said casing being formed to provide a plurality of passageways for distributing said current of air, and means for directing said air from said passageways toward the radiator.

20 3. The combination with a casing for containing a liquid medium, of a plurality of spaced heat radiators connected to said casing, and cooling apparatus therefor comprising a housing associated with each radiator, means mounted within said housing for creating a current of air, and means including said housing for directing said current of air onto the surface of said radiators.

25 4. In combination, a casing, a plurality of radiators connected to said casing for cooling a fluid contained therein, a separate air cooling apparatus for each of said radiators comprising a bifurcated housing mounted thereon having air outlet ports on opposite sides thereof, means within said housing for producing an air current, and means including said housing for directing said air current upwardly along the radiating surface of said radiator.

30 5. In combination, a plurality of separated parallel vertically elongated heat radiating elements, a cooling device for each of said elements comprising a substantially conical housing mounted on said elements, 45 means for effecting the passage of a current of air through said housing, and means for directing said current of air upwardly near the radiating surface of said elements.

50 6. The combination with a casing, a liquid medium in said casing, and a plurality of radiating units connected to said casing and traversed by said liquid medium, of cooling fluid-directing structures associated individually with said radiating units, and means 55 comprising a motive device associated with each of said structures for passing a cooling fluid therethrough.

60 7. The combination with a casing, a liquid medium in said casing, and a plurality of radiating units connected to said casing and traversed by said liquid medium, structures associated individually with said units for directing a cooling fluid in a plurality of directions with respect thereto, and means 65 comprising a motive device associated with

each of said structures for passing a cooling fluid therethrough.

8. The combination with a casing, a liquid medium in said casing, and a plurality of radiating units connected to said casing and traversed by said liquid medium, structures associated individually with said units for directing a cooling fluid in a plurality of substantially opposite directions with respect thereto, and means comprising a motive device associated with each of said structures for passing a cooling fluid therethrough. 70

9. In a cooling system, a tank containing fluid to be cooled, a plurality of cooling radiators spaced about the tank and connected adjacent the top and bottom thereof to permit circulation of the fluid through the radiators, means for directing air along the surfaces of the radiators comprising separate casings associated with the several radiators and provided with air outlet ports on opposite sides thereof, and a separate blower unit within each casing. 75

20 10. In a cooling system, a tank containing fluid to be cooled, a plurality of cooling radiators spaced about the tank and connected adjacent the top and bottom thereof to permit circulation of the fluid through the radiators, each radiator comprising a plurality of spaced fluid-conducting members, and means for directing air upwardly along said fluid-conducting members from opposite sides of a radiator comprising a casing mounted on the radiator and a blower unit within said casing. 80

25 In testimony whereof, I have hereunto subscribed my name this 9th day of February, 1928.
